CLAIM

The ornamental design for a universal lid for pots and pans, as shown and described.

DESCRIPTION

FIG. 1 is a top perspective view of a universal lid for pots and pans according to a first embodiment of our new design; FIG. 2 is a first bottom perspective view thereof, FIG. 3 is a second bottom perspective view thereof, taken opposite the first bottom perspective view; FIG. 4 is a first side view thereof; FIG. 5 is a second side view thereof, taken opposite the first side view of FIG. 4; FIG. 6 is a first end view thereof; FIG. 7 is a second end view thereof, taken opposite the first end view of FIG. 6; FIG. 8 is a top view thereof; and, FIG. 9 is a bottom view thereof. The dash-dash broken lines in the drawings depict portion of the universal lid for pots and pans that form no part of the claimed design. The dot-dash-dot broken lines in the drawings define the bounds of the claimed design and form no part thereof.
